(57) **CLAIM**

The ornamental design for a lens cap, as shown and described.

DESCRIPTION

FIG. 1 is a top perspective view of a lens cap showing my new design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom plan view thereof.

The broken lines in the drawings depict portions of the lens cap, specifically the back opening and a specifications label, that form no part of the claimed design.
